UNITED STATES PATENT OFFICE.

WILLIAM HENRY KELSO, OF SAN FRANCISCO, CALIFORNIA.

GAS-HEATER.

1,377,890.

Specification of Letters Patent. Patented May 10, 1921.

Application filed May 24, 1918. Serial No. 236,345.

To all whom it may concern:

Be it known that I, WILLIAM H. KELSO, a citizen of the United States, residing at San Francisco, in the county of San Francisco and State of California, have invented new and useful Improvements in Gas-Heaters, of which the following is a specification.

This invention is an improved gas heater, the object of the invention being to provide 10 an improved heater in which gas is used as the fuel, and which serves to ventilate the room in which it is used without causing drafts in the room; which utilizes a much greater percentage of heat units than heretofore; which 15 prevents noxious gases from being drawn off into the room, and which discharges all the products of combustion into the flue or chimney so that the same are carried off.

With the above and other objects in view 20 20 the invention consists in the construction, combination and arrangement of parts hereinafter described and claimed.

In the accompanying drawings:—

Figure 1 is an elevation of a gas heater 25 constructed and arranged in accordance with my invention, and with the casing and the air intake partly in section.

Fig. 2 is a vertical transverse sectional view of the same.

Fig. 3 is a detail vertical sectional view on a larger scale of the air intake, the fan and burner.

Fig. 4 is a fragmentary view of a portion of the casing.

In the embodiment of my invention, I provide a heating coil 1 which in practice may be made of stove pipe of suitable diameter and in which the convolutions are superposed so that the heating coil is vertical. A suitable casing 2 is also provided in which the coil is arranged and preferably the casing has openings 2^a. An escape pipe 3 leads from the upper end of the coil to a flue or a chimney.

I also provide an air intake element 4 which is here shown as having a vertical intake arm which extends downwardly through the floor. The said intake element is here shown as a pipe which is divided by 50 a partition 6 into a duct 7 which discharges into the lowermost convolution of the heat coil and a duct 8 which discharges into a

casing 9 in which an electric fan 10 is arranged. A pipe 11 leads from the casing 9 and is bent over one side of the heating coil 55 and extends downwardly within the heating coil as at 12 so that the air which is drawn through the duct 8 by the fan is discharged among the convolutions of the coil and is thoroughly heated thereby and finds its way 60 into the room through the openings 2^a in the casing and hence serves to thoroughly ventilate the room and to supply the same with an abundant quantity of heated fresh air.

The burner 13 is here shown as a Bunsen 65 burner but within the scope of my invention may be of any suitable type or construction and is arranged in the lower end 14 of the heating coil. Said end 14 has an opening 15 provided with a hinged closure 15' to permit 70 the burner to be readily lighted and preferably a spring 16 is also used to normally keep the closure in closed condition. A suitable opening 17 in the casing affords access to the interior, the said opening being normally closed by a closure 17'. To protect the intake end 14 of the heating coil I provide a lining 18 which is in practice preferably a tile and is arranged and held above the burner. 80

It will be understood that owing to the length and extent of the heating coil the heat from the burner is fully utilized so that a greater economy of the fuel gas is effected and, moreover, the heater is highly efficient 85 for heating purposes. When the electric fan is in operation fresh cold air from the exterior is discharged in the space surrounded by the convolutions of the heating coil and is heated thereby and discharged into the room 90 so that the heater also serves to effectually ventilate the room in which the same is used.

While I have herein shown and described a preferred embodiment of my invention I would have it understood that changes may 95 be made in the form, proportion and construction of the several parts without departing from the spirit of my invention and within the scope of the appended claim.

Having thus described the invention, what 100 is claimed as new is:—

In a heater of the class described, an air heating coil, a casing surrounding said coil and having openings therein, an air intake

pipe communicating with the interior of the coil at one end thereof, a burner arranged in the coil at the point of communication with the said air intake pipe, a blower fan having 5 a casing connected directly with the air intake pipe to be supplied with air therefrom and an air delivery pipe leading from the

fan casing and extending into the coil casing and arranged to discharge in the space surrounded by the convolutions of the coil ad- 10 jacent the bottom thereof.

In testimony whereof I affix my signature.

WILLIAM HENRY KELSO.
